UNITED STATES PATENT OFFICE.

EZEKIEL JONES, OF BOSTON, MASSACHUSETTS.

SHOE-POLISHING MACHINE.

1,139,531.

Specification of Letters Patent. Patented May 18, 1915.

Application filed May 25, 1914. Serial No. 840,745.

To all whom it may concern:

Be it known that I, EZEKIEL JONES, a citizen of the United States, and resident of Boston, in the county of Suffolk and State 5 of Massachusetts, have invented certain new and useful Improvements in Shoe-Polishing Machines, of which the following is a specification.

This invention relates to shoe-polishing 10 machines, and its purpose is to provide an apparatus whereby shoes in use may be speedily and easily polished by the wearer, while he is seated.

Of the accompanying drawings, which 15 represent the invention somewhat diagrammatically: Figure 1 is a side elevation, partly in section, of my shoe-polishing apparatus, portions thereof being broken away to show clearly various parts of the mechanism. Fig. 2 is an elevation, partly in section, of the right-hand end of the machine, with reference to Fig. 1. Fig. 3 is a transverse vertical section on line 3—3 of Fig. 1, showing the parts as they would appear 20 when viewed toward the left of Fig. 1, on an enlarged scale. Fig. 4 is a horizontal section, on a reduced scale, indicated by line 4—4 through the tilting table shown in Fig. 1. Fig. 5 is a detail view of the clutch-connection for the brushes. Fig. 6 is a side view of a portion of the magazine or turret disk shown in elevation in Fig. 2. This figure shows a slot for the reception of a brush shank or the shank of a blacking-container, 25 and shows the edges of retaining members whereby the shank is removably held in the turret slot. Fig. 7 is a plan view of the retaining means shown by Fig. 6. Fig. 8 is a plan view of a blacking-container adapted 30 to be mounted in the turret.

The same reference characters indicate the same parts wherever they occur.

With reference to the drawings, a base member is indicated generally at 10 in Figs. 45 1 and 2, said base member being hollow and forming a chamber of U-shaped vertical cross section. Mounted to slide in the vertical cylindric portions 11 and 11' of the base member are plunger pedestals 12 and 50 12' provided respectively with heads 13 and 13' in which is mounted a transverse rod 14 held against movement by set screws 127. Loosely mounted on the ends of the rod 14

are bearing pieces 15 and 15' for a bed or table 16. The table 16 comprises three layers, preferably of metal, slotted as shown by Fig. 4, for a purpose presently to be described.

Slidably mounted upon the table 16 is a carriage indicated generally at 19, said carriage having columns 20 and 21 bearing a casing 22 through which passes longitudinally a shaft 23 which receives rotation through a flexible shaft 24 from any suitable source of power, such as an electric 60 motor, not shown. The shaft 23 is journaled in the casing 22 and is provided with collars 23' whereby it is held against end movement. Shafts 25 and 26 extend downwardly from the casing 22 through the columns 20 and 21 of the carriage and into the slots 17 and 18 of the table. These shafts are provided near their upper ends with shoulders 27 which abut against the upper surface of the columns of the carriage and 70 prevent endwise movement of the shafts in a downward direction. Between the ends of the shafts 25 and 26 are mounted sprocket wheels 28, a portion of the columns being 75 cut away for the reception of the sprocket 80 wheels. The sprocket wheels 28 are connected by an endless chain 29, the purpose of the chain being to insure equal rotation of the shafts 25 and 26. Affixed to the upper ends of shafts 25 and 26 are bevel gears 85 30 and 31. The teeth of the gears 30 and 31 mesh with a plurality of bevel gears 32, 32, and 33, 33, which are mounted to rotate independently on the shaft 23 but are held against movement longitudinally thereof. 90 Each of the gears 32 and 33 is formed with an elongated shank at the end of which are provided two pairs of laterally extending lugs or ears 34 (Fig. 3). Pivoted midway of their length between each pair of lugs 34 95 are gripping members 35. Splined upon the shaft 23 and rotatable therewith though capable of movement longitudinally thereof are tapered sleeves 36 and 36', best shown by Fig. 1, which sleeves, when caused to contact with the complementary gripping members 35 form clutch mechanism.

On the lower ends of shafts 25 and 26 are rigidly mounted pinions 37 and 38 respectively. The teeth of these pinions mesh 105 with complementary teeth which project into

the curved slots 17 and 18 from the middle layer of the tongue-like portions of the table 16 which are defined by the slots. See Fig. 4.

5 Standards 39 and 40 mounted upon the casing 22 of the carriage afford bearings for a looped rod 41, to the lower stretch of which are affixed pendent shipping members 42, 42 and 43, 43, these shipping members being held in position on the rod by setscrews so as to be capable of adjustment. The lower end of each member 42 is bifurcated so as to straddle one of the members 36', and each of the members 43 is similarly 10 formed to straddle a member 36, the members 36 and 36' having annular shoulders between which is a groove for the reception of the bifurcations.

A hollow vertical post 44 mounted to turn 20 in an arched base member 45 is shown at the right of Fig. 1. To the upper end of the post is affixed an elbow 46. In the free end of the elbow is a bearing for the axle 50 of a magazine or turret disk 47 on which are 25 mounted a plurality of brushes and blacking-containers. This construction permits the turret disk to move bodily in a horizontal plane about post 44 and to revolve in vertical planes on its axle 50. Shown behind 30 the tools of the turret in Fig. 1 is the foot rest 48 of a bootblack's chair. The remainder of the chair is omitted from the drawing, but it is to be understood that any chair provided with a foot rest may be used. Extending from convenient points of attachment 35 on the chair or on a wall or partition adjacent the back of the chair are arms 52 and 53 the free ends of which afford bearings for a vertical rod 54. Mounted upon the upper end of the rod 54 in a position convenient 40 for manipulation by the left hand of the person sitting in the chair, is a hand lever 51. Rotation of this lever in a horizontal plane transmits motion through rod 54 to a bevel gear 55 affixed to the lower end thereof. This gear meshes with a bevel gear 56 45 affixed to the end of a horizontal rod 57 which has a bearing in a member 58. The rod 57 extends through and has a bearing in the arched base member 45, the rod being 50 provided with a collar 59 which abuts against the outer surface of the member 45 and assists in holding the shaft against end movement. Mounted upon the end of the shaft 57 which underlies the arch is a bevel gear 60. This gear meshes with a complementary gear 61 affixed to the lower end of the rod 62 which passes upwardly through the hollow post 44. The rod 62 is mounted 55 in bearings in the upper and lower ends of the post 44. At the upper end of the rod 62 is a bevel gear 63 which meshes with a gear 64 affixed to the turret axle 50. From this description it will be apparent that by rotating 60 the hand lever 51 in a horizontal plane

the turret disk may be caused to revolve on and with its axle 50 until any desired brush or container mounted thereon may be brought into contiguous relation with the right-hand end of shaft 23, on which is mounted a clutch 65, conventionally shown in horizontal section in Fig. 5, the view of this clutch being obscured in Fig. 1 by elbow 46. The clutch 65 as shown comprises a cylindrical body apertured throughout its length, one end of the aperture being occupied by shaft 23 to which the clutch may be affixed in any desired manner, as by setscrews, not shown. The aperture is provided with a recess in which are oppositely arranged springs 65' of strip steel attached in any desired manner to the clutch body and formed so as to bulge toward the longitudinal median line of the clutch, this arrangement of the springs causing them to engage frictionally a body introduced into the free end of the clutch, as for instance, the shank 66 of a brush. I do not confine myself to a clutch of this particular construction, but may use any suitable friction clutch.

The brush-receiving slots of the turret are provided with resilient retaining members 47, as shown by Figs. 6 and 7, which allow insertion and removal of the brushes yet hold them in the slots until force is applied to remove them. The slots for the blacking-containers are likewise provided with the members 47'.

Means whereby other mechanism of the apparatus is manipulated are shown in Fig. 2. Within easy reach of the right hand of the operator seated in the chair, is a handle 67 affixed to the upper end of a piston rod 68 which is mounted to slide through the stuffing box in the head 69 of a cylinder 70. The cylinder is supplied with water from any suitable source. When the handle 67 is depressed, the water in the cylinder 70 and in the conduit 172 is forced downwardly by the pressure of the piston head 71, the level of the water in base member 10 is raised, pressure is applied to the base of the plunger pedestals 12 and 12', and the pedestals with their superstructure are thereby raised to a degree corresponding with the depth of depression of the handle 67. Although I have not shown stuffing boxes for the cylinders 11 and 11', it is to be understood that they will be used. A detent 72 projecting laterally from the upper end of the rod 68 may be caused to coact with the teeth of a ratchet bar 72' which is mounted at the top of the cylinder and extends in a direction parallel to that of the rod 68. To cause this coaction the handle 67, after being depressed to the desired position, is turned so that the detent is brought beneath one of the bar teeth, and the upward pressure of the liquid in the cylinder causes the detent 72 to abut

against the bottom of the tooth. To release the detent and allow the table to fall the handle is turned until the detent is clear of the coacting tooth, when the handle will rise 5 to its normal position.

Referring to Fig. 2,—arranged in series at the right of the chair are hand levers 73, 74 and 75. The lower end of the lever 75 is affixed to a rockshaft 76 which has a bearing 10 at one end in a member 77 similar to the member 79 at the lower right of Fig. 1. The rockshaft 76 is also provided near its other end with a bearing 80 secured to the floor. At the left-hand end of the rockshaft 76 is 15 affixed an arm 81 which extends upwardly and is pivoted at its upper end to one end of a bar 82. (Fig. 1.) The other end of the bar 82 is mounted on a stud 83 projecting horizontally outward from the bearing piece 20 15 of the table, the axis of the pivot 83 being in vertical line with the axis of axle 14 when the lever 75 is in its median or neutral position. Movement of the lever 75 thus imparts motion to the rockshaft 76, which motion is transmitted to the vertical bar 81, causing it to describe an arc concentric with that described by the lever 75. The motion imparted to the rod 82 causes the table to tilt. The lever 75 is provided with a spring 25 latch, the handle of which is indicated at 84. This handle 84 is grasped in conjunction with the handle of the lever, and pressure on the handle 84 causes the rod 85 of the latch to be drawn upwardly. The rod 85 passes 30 through apertured lugs 88 and 87 and is provided with a collar 86 which normally abuts against the upper surface of the lug 87. The rod 85 is provided at its lower end with a detent 89 which is arranged to enter 35 40 into the notches in the upper surface of the member 77. When the handle 84 is pressed by the hand grasping the handle of lever 75 the detent is raised and the lever may be moved to any desired position to tilt the table 16 45 and its superstructure. The handle 84 is then released and the table is held securely in place by the detent 89 of the lever latch, which is projected into a notch in member 77 by the compression spring 90 which co- 50 55 acts with the lug 88 and collar 86 to force the rod 85 and detent 89 downwardly.

Lever 74 is similar in construction to lever 75. This lever, however, is affixed to one end of a sleeve 91 mounted on the shaft 76. 55 This sleeve has at its other end a laterally extending arm 92 which is pivoted at its upper end to one end of a rod 92' which comprises two portions connected by a turnbuckle 94, the rod 92' being pivoted at its 60 other end between lipped ends of frame members 93 and 93'. The turnbuckle regulates the arc through which the frame members swing. From their lipped ends the frame members curve upwardly, as shown 65 best by Fig. 1, to points which when the

table is level are in the vertical plane of the longitudinal median line of the member 14. The frame members pass upwardly through slots 96 and 96' respectively, provided in the table, where they are mounted on pivots 95 70 and 95', best shown by Fig. 3, arranged in the middle layer of the table. The frame members are connected near their upper ends by a crosspiece 97 (Figs. 2 and 3) which serves to increase their rigidity. A cross- 75 bar 98 extends parallel to the crosspiece 97, the bar 98 being mounted so as to slide both in the directions of its ends and perpendicularly thereto in slots provided in the members 93 and 93'. The upper stretch of the 80 looped rod 41 of the carriage passes transversely through the bar 98, the bar 98 being provided with a laterally extending stud on which is mounted a friction shoe 100 held normally above and away from the rod 41 85 by a spring 101. Mounted at the extreme upper end of the member 93 is a flat bar 102 of springy metal. This bar has a ninety-degree twist near its point of anchorage to the member 93, and near the upper end of 90 the frame member 93' the bar 102 is given another ninety-degree twist, an upward curve, and is then turned downwardly. The bar 102 normally springs upwardly out of engagement with the shoe 100; but by the 95 construction just described, when the bar is in operative position, it has edge contact with the friction shoe 100 and is capable of considerable lateral flexure and edgewise flexure. Sidewise movement of the carriage 100 will cause the crossbar 98 to receive endwise movement, but the shoe 100 will remain in contact with rod 41 and with the resilient rod 102.

When the lever 74 is moved, its motion is 105 transmitted to the hollow shaft 91, arm 92, rod 92', and the frame members 93 and 93'. The upper portions of the frame members are thereby swung in a direction opposite to that given to the lever, and the crossbar 98 110 slides loosely upon the rod 41, arcuate movement of the bar 98 being avoided by its play in the slots of the frame members 93 and 93' through which the bar extends.

Lever 73 (Fig. 2) is affixed to a hollow shaft 104 which is mounted to oscillate on hollow shaft 91. An arm 105 extends upwardly from the end of shaft 104 in a line parallel with the lever 73. Attached to the upper end of the arm 105 is one end of a flexible connection 106, such as a cord or chain. The other end of the cord or chain is attached to the free end of spring rod 102. Mounted on a stud projecting horizontally 120 from the inside wall of the bearing piece 15' of the table is a sheave 107 which coacts with the flexible connection 106 to change the direction of power applied by the lever 73 whereby the rod 102 is drawn downwardly. The table 16 is apertured at 16' 125 130

(Fig. 4) for the passage therethrough of connection 106.

The operation of the machine is effected as follows: If it be assumed that the carriage is in the position shown by Fig. 1 and indicated by the position of gears 37 and 38 in Fig. 4, the operator will grasp with his right hand the lever 73 and draw it backwardly as far as possible. By means of the intervening connections the force applied to the lever is caused to draw downwardly the rod 102 (Figs. 2 and 3) which in turn depresses the shoe 100 and causes it to bear against the rod 41, the latter being thereby held rigidly with relation to the crossbar 98. The operator now grasps lever 74 and draws it backwardly. This tilts the frame members 93, 93' and moves the crossbar 98 in a substantially horizontal path away from the operator, or toward the left of Fig. 1. The crossbar 98 rises in the slots of the frame members because their line of travel is a downward curve, but sufficient pressure is maintained on the rod 41 by the shoe 100 to prevent the rod from slipping through the crossbar 98. When the lever 74 has been drawn backward sufficiently, the pendent shipping members 43 will have wedged the splined and tapered sleeves 36 between the gripping members 35, the members 35 being thus tilted to grasp the shanks of the bevel gears 33 which mesh with the bevel gears 30 and 31. By any suitable means, such as a switch (not shown) which may be located at any convenient point near the operator, the motor or other source of power which imparts rotation in a clockwise direction to the shaft 23 through flexible shaft 24 is caused to operate. The bevel gears 33 on shaft 23 now turn therewith and cause bevel gears 31 to revolve, the rotation being transmitted through shafts 25 and 26 to the small gears 37 and 38, the teeth of which mesh with the teeth in the slots 17 and 18 of the table 16. The carriage 19 is thus caused to travel toward the operator until it reaches the limit of its movement in that direction. The lever 74 is then pushed forwardly to its neutral position, which causes the traversing mechanism of the carriage to become inoperative, although the shaft 23 still continues to revolve. The lever 73 may be allowed to retain its operative position until movement of the carriage is again required. A collar 108 affixed on the upper stretch of rod 41 and capable of adjustment longitudinally thereof may be positioned so that the standard 39 will strike it, and, overcoming the friction of the shoe 100 on the rod 41, throw the carriage-moving clutch mechanism out of operative position if the gears 37 and 38 should be carried too near the ends of the slots, thereby guarding against

breakage of gear teeth and the teeth in the slots 17 and 18. After such stoppage of the carriage movement it would only be necessary to place the levers 73 and 74 in their neutral or inoperative position in order to readjust the crossbar 98 and rod 41 for restarting.

Assuming now that the carriage is occupying its extreme forward position at the left of the shoe 49, for present purposes it may also be assumed that the turret is in a position where the brushes mounted thereon are parallel with the clutch 65 on shaft 23. Grasping the lever 51 with his left hand, the operator moves the lever in a horizontal plane. If the lever 51 be turned in a clockwise direction the turret 47 will revolve clockwise in a vertical plane. If desired a counter clockwise movement may be imparted to the lever 51, which will give counter-clockwise movement to the turret. When the brush desired for first use on the shoe—say, for instance, brush B in Fig. 2—has been brought in alinement with the clutch 65 on the end of shaft 23, the turret may be held stationary by the left hand of the operator and the carriage is operated to move forwardly until the shank 66 of the brush is driven into the clutch, in which it will be gripped and securely held by the springs 65'. The left hand of the operator may then swing the turret bodily to the left and away from the brush gripped by the clutch, this action causing the members 47' to spring apart and release the brush from the turret.

After the operations described in the last paragraph have been performed, the carriage is at its forward position at the left of the shoe, and movement of the shaft 23, which has been continuous, causes the revolution of the brush B which by the insertion of its shank into the clutch has been brought into position to polish the shoe 49. Lever 73, if at neutral, is now drawn backwardly, and lever 74 is grasped and projected forwardly, these operations resulting in rod 41, its pendent shippers and the tapered sleeves 36' being moved toward the operator, thus causing the grippers 35 to engage the shanks of gears 32 and impart rotation thereto, the gears 32 meshing with the teeth of bevel gears 30 and 31 which impart rotation through shafts 25 and 26 to the gears 37 and 38 at the lower ends of the shafts. The gears 37 and 38 are carried along the slots 17 and 18 by their coaction with the teeth in the slots, the carriage being thus moved in a corresponding path.

While the carriage is in motion and the revolving brush is being carried about the shoe 49, the brush may be elevated or lowered by the depression or elevation respec-

- tively of handle 67, which causes the table, and consequently the brush, to rise in the manner hereinbefore described. By turning the handle 67 sufficiently to keep the 5 detent out of contact with the teeth of the ratchet 72' and by alternately depressing the handle and allowing it to rise, the brush may be caused to work in different planes. By moving the lever 75 to the rear, the end 10 of the table 16 nearer the operator will be caused to tilt downwardly, the brush consequently operating obliquely. By pushing lever 75 forwardly the table end nearer the operator will be tilted upwardly and the 15 brush will operate at another angle. The angularity of the application of the brush to the shoe may therefore be varied at will.
- When the brush has reached the right-hand side of the shoe and has been carried 20 to its extreme forward position, the lever 74 is drawn rearwardly as far as possible. The travel of the carriage is thus reversed, and the revolving brush will be carried back to its extreme forward position at the left of 25 the shoe, its path being governed by the curve of the slots, the depression of the handle 68 and the position of the lever 75. When the brush arrives at its forward position at the left of the shoe, if a change of 30 brushes is desired the table will be brought to its normal level. The empty slot of the turret disk may now be manually swung back to the position in which it presented the shank of brush B to the clutch 65, so 35 that the spring member 47' will pass above and below the shank 66 between the collars 66' and 66''. The carriage is now caused to back away from the turret, while the turret is held stationary by the left hand of the 40 operator, whereby the clutch 65 will be withdrawn from the shank 66 of the brush. The lever 51 at the left of the operator may now be rotated to carry brush B away on the turret and bring the shank of brush A 45 into position to be fitted into the clutch 65, and when the clutch has been moved toward and has grasped the shank of the brush the turret is either rotated vertically or swung away horizontally to dislodge the brush from 50 the slot in the turret. By turning the lever 51 a blacking-container C is revolved into position whereby when the brush is at the left side of the shoe its bristles are brought into contact with the blacking, the brush being 55 caused to enter into the container as deeply as desired by grasping the turret disk and swinging it toward the brush the desired distance. The blacking is applied to the shoe by the revolving brush.
- 50 In order to polish the back of the shoe it is most convenient to give the shoe an angular position with relation to the foot rest, using the heel as a pivot. The toe of the shoe shown in Fig. 2, for instance,
- would be turned to the right in order to 65 polish the left half of the back of the shoe, and when the brush is at a corresponding position on the other side of the shoe the toe would be swung to the left in order to 70 polish the right half of the back of the shoe. 70
- I claim:
1. In a shoe-polishing machine, a table, a carriage movably mounted on said table, a revolute shaft having bearings in said carriage, a brush-clutch on said shaft, and carriage-moving mechanism arranged to transmit motion from said shaft to move said carriage and shaft bodily with relation to said table. 75
  2. In a shoe-polishing machine, a table, a carriage movably mounted on said table, a revolute brush-shaft having bearings in said carriage, carriage-moving mechanism arranged to transmit motion from said shaft to move said carriage and shaft bodily with 80 relation to said table, and manually operative means for raising and lowering said table. 85
  3. In a shoe-polishing machine, a table, a carriage movably mounted on said table, a revolute brush-shaft having bearings in said carriage, carriage-moving mechanism arranged to transmit motion from said shaft to move said carriage and shaft bodily with 85 relation to said table, and manually operative means for raising and lowering said table. 90
  4. In a shoe-polishing machine, a table, a carriage movably mounted on said table, a revolute brush-shaft having bearings in said carriage, carriage-moving mechanism arranged to transmit motion from said shaft to move said carriage and shaft bodily with 95 relation to said table, and manually operative means for connecting and disconnecting said carriage-moving mechanism with said 100 shaft. 105
  5. In a shoe-polishing machine, a table, a carriage movably mounted on said table, a revolute brush-shaft having bearings in said carriage, carriage-moving mechanism arranged to transmit motion from said shaft to move said carriage and shaft bodily with 110 relation to said table, and means for automatically disconnecting said carriage-moving mechanism from said shaft. 115
  6. In a shoe-polishing machine, a table, a carriage movably mounted on said table, a revolute brush-shaft having bearings in said carriage, carriage-moving mechanism arranged to transmit motion from said shaft to move said carriage and shaft bodily with 120 relation to said table, said mechanism including manually adjustable means by which the direction of movement of said carriage may be reversed. 125
  7. In a shoe-polishing machine, a table, a carriage movably mounted on said table, a revolute brush-shaft having bearings in

- said carriage, carriage-moving mechanism arranged to transmit motion from said shaft to move said carriage and shaft bodily with relation to said table, manually operative means for raising and lowering said table, manually operative means for tilting said table, and manually operative means for connecting and disconnecting said carriage-moving mechanism with said shaft.
- 10 8. In a shoe-polishing machine, the combination with means for engaging and axially revolving a brush, of a brush-magazine manually adjustable to transfer a brush to said means when said means is in a predetermined position.
- 15 9. In a shoe-polishing machine, the combination with means for engaging and axially revolving a brush, of a magazine for detachably holding a plurality of brushes, said magazine being manually operative to transfer any one of said brushes to said means when said means is in a predetermined position.
- 20 10. In a shoe-polishing machine, the combination of means for frictionally holding and axially revolving a brush, and a magazine for detachably holding brushes and having a blacking container thereon, said magazine being manually adjustable to transfer a brush held thereon to said means and to position said blacking container to supply blacking to the transferred brush.
- 25 11. In a shoe-polishing machine, the combination with rotary means for axially revolving a brush, of a magazine for a plurality of blacking containers, said magazine

being manually adjustable to bring the contents of any one of said blacking-containers into contact with a brush held by said rotary means.

40 12. In a shoe-polishing machine, the combination with rotary means for holding and axially revolving a brush, of a magazine for detachably holding brushes and blacking-containers, said magazine being manually adjustable to transfer any one of said brushes to said rotary means and to position any one of said blacking-containers to supply blacking to a brush in said rotary means.

45 13. In a shoe-polishing machine, the combination with means for frictionally engaging and reciprocating a brush, of a magazine manually adjustable to dislodge a brush from said means when said means are receding from a predetermined position.

50 14. In a shoe-polishing machine, the combination with means for frictionally engaging and reciprocating a brush, of a magazine manually adjustable to dislodge a brush from said means when said means are receding from a predetermined position, said magazine having retaining devices whereby upon dislodgment of said brush from said means the brush is automatically held upon said magazine.

55 In testimony whereof I have affixed my signature, in presence of two witnesses.

EZEKIEL JONES.
